HUMIDIFIER

Karl Flury, Dietikon, Switzerland, assignor to Defensor
AG, Zurich, Switzerland, a Swiss corporation

Filed Nov. 8, 1967, Ser. No. 9,329

Claims priority, application Switzerland May 16 1967

Term of patent 14 years

(Cl. D23—146)

FIG. 1

FIG. 2

FIG. 4

FIG. 3

FIG. 5

FIG. 6

FIG. 7

FIGURE 1 is a perspective view of the humidifier embodying my new design;

FIGURE 2 is a front view thereof;

FIGURE 3 is a rear view thereof;

FIGURE 4 is a side view thereof;

FIGURE 5 is a top plan view thereof;

FIGURE 6 is a bottom plan view thereof; and

FIGURE 7 is an enlarged fragmentary view of the perforated covering panel for the top and sides of the humidifier.

The undisclosed remaining side of the humidifier is identical to the side shown in FIGURE 4.

The dominant features of my design reside in the portions shown in full lines.

I claim:

The ornamental design for a humidifier, substantially as shown and described.
